UNITED STATES PATENT OFFICE.

JOHN S. BEALL, OF PORTLAND, OREGON, ASSIGNOR TO COAST CULVERT AND FLUME CO., OF PORTLAND, OREGON, A CORPORATION OF OREGON.

BENDING ROLL.

Application filed October 8, 1924. Serial No. 742,383.

My invention relates to bending rolls wherein the same are used in forming cylindrical materials from sheets or bars, or the like and consists primarily of three 5 rolls mounted in a frame support upon a base and adapted to being driven, and to having the center lines of the same changed in relation with each other. Further novelty resides in the fact that the center of the 10 upper roll may be maintained at an equal or unequal distance from the center lines of each of the lower rolls, and that the smaller of the two lower rolls has a larger diameter at the center and gradually tapers 15 toward either end of that portion used for bending purposes. I have provided new and novel means for releasing the bearing from the outboard end of the upper roll; the same being accomplished by the application 20 of a fluid under pressure within a cylinder for actuating a piston.

New and useful means have been provided for the raising and lowering of each of the lower rolls independently of the 25 other, by power means, that accomplishes the work rapidly and efficiently. I have provided a machine that imparts uniform curvature to all parts of the material to be bent.

With these and incidental objects in view 30 the invention consists in certain novel features of construction and combination of parts, the essential elements of which are set forth in the appended claims and a preferred form of embodiment of which is hereinafter shown with reference to the drawings which accompany and form part of this specification.

I attain these objects by the mechanism 40 illustrated in the accompanying drawings, in which—

Figure 1 is a side elevation of the assembled machine looking from the control lever side.

Fig. 2 is an end elevation of the driving 45 end of the machine.

Fig. 3 is a sectional view taken on line 3—3 of Fig. 2, looking in the direction indicated.

Fig. 4 is a sectional view taken on line 4—4 of Fig. 3, looking in the direction indicated.

Fig. 5 is a sectional view taken on line 5—5 of Fig. 3 looking in the direction indicated.

Fig. 6 is a sectional view taken on line 6—6 of Fig. 1 looking in the direction indicated.

Fig. 7 is a sectional view of the central bearing support of the upper roll. 66

Fig. 8 is an outboard end view of the assembled machine.

Fig. 9 is a sectional view of the fluid operated cylinder located at the outboard end of the machine. 65

Fig. 10 is a sectional view taken on line 10—10 of Fig. 1 looking in the direction indicated.

Fig. 11 is a sectional view taken on line 11—11 of Fig. 3 looking in the direction indicated. 70

Fig. 12 is a detached side view of the tapered roll.

Like reference characters refer to like parts throughout the several views— 75

I have found that best results are obtained by using a structural steel base 1, but I do not wish to be limited to any particular form of construction, for the base for a cast frame may be equally well used. Secured 80 to the base and acting as a frame structure to which the superstructure and the operating mechanism is secured are plate members 2 which may be secured to the base by bolting or riveting or welding. 85

I have illustrated four of these frame supports mounted upon the base, but do not wish to be limited to any specific number, as the number will depend upon the length of the rolls and the size and character of the 90 materials to be formed upon the machine.

An electric power unit 3 serves to impart operating energy to the machine, the same being mounted within the frame and having a control box 4 mounted in a convenient location to the operator of the machine. 95

Mounted upon the shaft 5 of the motor is a pinion 6 that is adapted to high speed use and that will carry the loads necessary in machines of this character. I have found the pinion of the silent operating type gives best results. The pinion 6 coacts with the gear 7 which is mounted upon the shaft 8 which is properly journaled within the frame structure. In machines of this character it is desirable that the rolls be driven in either direction, this is accomplished in driving the top, or superposed roll, by the following gear arrangement. Secured to the shaft 8 is pinion 9 meshing with pinion 10 that is 100 105 110

secured to the clutch hub on shaft 11. The shaft 11 is journaled within the frame structure, and has a clutch shifting mechanism 12 interposed between the shaft, that is double acting, in order that either end of the shaft may be driven. The driving end 13 serves to connect and disconnect the shaft 11 having the driving pinion 14 secured thereto which coacts with the gear 15 mounted upon shaft 16 which is also journaled within the frame structure.

Mounted upon the shaft 16 is the driving pinion 17 which meshes with the master gear 18 that is mounted upon the superposed roll 21 and serves to impart rotation to the same. The roll 21 is journaled within the pillow block 20 at, or near the inboard end of the roll, and is adapted to being moved within the necessary limits to serve to adjust the location of the block to the ordinary requirements of the machine. Bearing 20^a serves as the bearing for the central location of the roll shaft and is so constructed, as shown in section in Fig. 7, to permit of certain changes in the alignment of the superposed roller. The train of gearing just outlined tends to drive the roll 21 in one direction. When the roll is to be driven in the opposite direction, the clutch 13 is disengaged and the clutch 22 is engaged with the shaft end 11^a which is in the same alignment with the shaft 11 and in fact is the same shaft having the clutches 13 and 22 attached thereto and one of which is out of engagement at all times when the shaft 11 is being driven. Pinion 23 is mounted upon the hub of the clutch 22 and is driven by the gear 24 being in mesh with the gear 25 which in turn meshes with the pinion 23. The gear 24 and the pinion 23 do not mesh with each other; this is best shown in the sectional drawing of Fig. 4. By driving the shaft 11 through the medium of an idler gear I rotate the shaft 11 in the opposite direction from that obtained in the previous drive just described and I therefore drive the roll 21, also in the opposite direction.

Disposed lengthwise of the machine, and below the top roll are two additional rolls 26 and 27, the same being adapted to independent drives for rotation in either direction and each adapted to being raised or lowered independent of the other. Each of these rolls has a roller support disposed between the ends and a bearing opposite the drive end, and both supports are adapted to being raised or lowered by power-driven screw means. Lever-manipulated, power-driven clutches are adapted to impart rotation, in either direction, to each of the rolls, as well as to raise, or lower, either of the supports for each roll. The distance of the longitudinal center lines of the lower rolls from the longitudinal center line of the upper roll is of an unequal distance, the ob-

ject being to permit of the manipulation of the rolls to produce a true cylinder from the sheet, or plate, stock being bent, or rolled. One of the lower rolls has a larger diameter at a point located between the ends of the rolling surface than at the ends and tapers in a uniform manner from the point of largest diameter to the end of the rolling surface in either direction. The roll is tapered for two reasons: first, for the purpose of strengthening the bending roll; second, to prevent the bellying of the material being rolled.

The superposed roller shaft 21 has a gear 28 thereon having specially constructed long teeth 29 for engagement with another gear 30 with equally long teeth 31. These gear teeth are made long to compensate for the movement of the roll in its up and down movement to compensate for the different thicknesses of material being rolled, or bent, and for the different curvatures to be imparted to the material as well. Mounted upon the roll shaft 26 is a second driving gear 33 adapted to coact with the idler pinion 34 mounted upon stub shaft 35 and mounted upon the roll shaft 27 is the gear 36 also adapted to coact with the idler 34. Thus as rotation is imparted to the superposed roll, rotation is also imparted to each of the lower rolls, so long as the gears 28 and 30 are in mesh with each other.

Located at a point between the end bearings of each of the lower rolls is an adjustable support yoke 37 adapted to being supported upon the upper end of the screw 38 and having rollers 39 journaled therein and made to conform to the diameter of the roll to be supported. The screw 38 is fitted to the worm wheel 40 so that as the worm wheel is rotated, the screw is raised or lowered because the same is threaded through the hub of the worm wheel. The worm wheel is journaled within the bearing 41 and is held in place as a thrust bearing. The bearing 41 is secured to the frame structure by suitable fastenings 42. Mounted upon the shaft 43 is a worm screw 44 that coacts with, and imparts the operating force to drive the worm wheel.

It is desirable that each of the lower rolls be adapted to being raised, or lowered at the end opposite the driving end as well as being raised or lowered at a point between the driving end and the end opposite, each independent of the other, this is accomplished by transverse shafts having clutches secured thereto and adapted to being driven, indirectly from the power unit mounted upon the frame of the machine.

Shaft 45 is adapted to being driven from the main power unit mounted upon the machine through a train of gearing heretofore described and having clutch members 46 and 47 attached thereupon and adapted to being

manipulated through the action of the shiftable member 48. The gears 52 and 53 are adapted to drive the shaft 45 through the action of the clutches 46 and 47, one set in one direction and the other set in the opposite direction of rotation. 49 is a sprocket attached to the shaft and adapted to drive the chain 49^a that also drives the sprocket 49^b secured to the shaft 50; through the connection of the clutch member 51 and is manipulated into and out of action by means of the shift arm 52. Shaft 50 and shaft 43 are adapted to being driven as a single shaft when clutches 54, 55, and 56 are engaged, or only such portion of the combined shaft may be driven as the operator may desire. The operation of these clutches determines which portion of the roll is to be raised, or lowered. Since the raising, or lowering of roll 37 is determined by the operator as above outlined it is apparent that the manipulation of roll 27 is accomplished without in any way interfering with the operation of either of the other rolls.

25 The independent driving of the roll 26 is accomplished in much the same manner as the drive of rotation as applied to roll 27 and is accomplished by drive chain 57 being driven by chain sprocket 58 secured to shaft 45. Chain 57 coacts with sprocket 59 secured to clutch shaft 60. Shafts 60 and 61 are secured together by means of clutches 62, 63 and 64 any one of which may be disengaged by the manipulation of the operating lever. Secured to these shafts are the worm wheels that cooperate with the worm wheels that are adapted to raise and lower the rolls at the desired location as heretofore described.

40 The outboard bearing 65 of the superposed roll 21 is adapted to engagement and disengagement with the roll by power means. This is made necessary because of the fact that if cylinders and the like are being formed, and the ends are closed the same may be removed from the rolls, only by shifting the same from the rolls in an endwise movement. Many times the rolls are under some pressure and the shifting of 45 the bearing, which in the larger sizes, are of substantial weight takes substantial energy to accomplish the same. The bearing 65 is connected by a link like structure to a barrel bearing 66 that surrounds the cylinder 67. Secured to the member 66 is a stirrup member 68 that is secured to the piston rod 69 by suitable means. The piston rod passes through the cylinder head 76 having a packing gland surrounding the same to insure a tight workable joint. Secured to the piston rod 69 is a piston member 71 that is adapted to work within the cylinder 70 and to having energy applied to actuate the same. 76 is a two-way valve located at the 55 outboard end of the machine and at a convenient position for the manipulation thereof, by the operator of the machine. A fluid under pressure, as water or compressed air or other suitable operating medium, is conducted to the valve through suitable piping 70 from a source outside of the machine. Leading from the valve to the cylinder are pipes 72 and 73 leading into opposite ends of the cylinder which is adapted to being manipulated in a reciprocating movement being applied to the piston within the cylinder. A sloping surface 77 is provided at the outboard end of the upper shaft to afford an easy engagement of the same within the bearing 65. The barrel section 66 of the 80 arm is adapted to form a working fit about the cylinder 67. In order that the strain may be transferred to the frame of the machine directly instead of being carried upon the cylinder 67 directly, a projection 75 is 85 provided having a pin therein adapted to engagement within a suitable bearing within the frame as shown in Fig. 9. When the bearing 65 is disengaged from the superposed roller, the pin 74 becomes disengaged 90 from the bearing within the frame, at which time the arm 75 may be rotated about the barrel support to permit of the removal of the rolled structure from the machine.

95 The stub axle 35 is held in position by the action of the link members 77 and 78 as shown in Fig. 5.

100 While the form of mechanism herein shown and described is admirably adapted to fulfill the objects primarily stated, it is to be understood that it is not intended to confine the invention to the one form of embodiment herein shown and described, as it is susceptible of embodiment in various forms all coming within the scope of the 105 claims which follow.

What I claim is:

1. In a machine of the class described, the combination of a longitudinal structural base, a structural frame mounted upon the base, journals secured within the frame, one upper and two lower rolls adapted to being revolved within the journals, power driven means adapted to revolve said rolls, means for shifting each of the lower rolls, a bearing supporting the outer end of the upper roll and adapted to be moved into and out of relation with said roll, a fluid pressure means to move said bearing into and out of relation with said upper roll, means permitting the rotation of the bearing about a horizontal axis when moved out of engagement with the upper roll, and means for transmitting the strain, when the roll is under pressure, from the bearing directly to the frame support.
2. In a machine of the class described, the combination of a frame structure, three rolls journaled therein, each roll adapted to being driven in either direction independent

of the others, one roll superposed above the others, the distance of the center line of the upper roll from the center line of each of the lower rolls adapted to being changed, 5 driven screw means for raising and lowering each of the lower rolls, means for centrally supporting each of the lower rolls while stationary and during the period of being raised or lowered, one of the lower 10 rolls having a larger diameter between than at the ends of the rolling surface, and journals supporting each roll within the frame structure.

3. In a machine of the class described, the 15 combination of a rigid frame structure, journaled bearings secured within the frame structure, an upper and two lower bending rolls adapted to being rotated within said journaled bearings, power means for rotating 20 the rolls in either direction, screw driven means for changing the radial distance between the upper roll and each lower roll, a movable bearing supporting the end opposite the driven end of the upper roll, 25 hydraulic means for engaging and disengaging said movable bearing with the upper roll, and means permitting the movable bearing to be rotated about a horizontal axis when so disengaged.

4. In a machine of the class described, the 30 combination of three power driven bending rolls, one superposed above the other two, the center line of which is maintained at a predetermined distance from the center line 35 of each of the lower rolls, a movable bearing supporting the upper roll opposite the driven end of said roll, hydraulic means for engaging and disengaging the movable bearing of the upper roll and said movable bearing adapted to being rotated about a horizontal axis parallel with the longitudinal axis of the upper roll when so disengaged.

5. In a machine of the class described, a 45 fabricated structural base, a frame, one upper and two lower bending rolls journaled within said frame, a power unit mounted upon the base, a control switch adapted to regulate the power unit, gearing adapted to 50 connect the power unit with each of the three bending rolls, means adapted to drive the bending rolls, selective manipulative means for raising or lowering either of the lower rolls, separate journaled bearings for 55 each of the bending rolls, a movable bearing for the end opposite the driven end of the upper bending roll, and hydraulic means for engaging and disengaging the movable bearing with the upper roll.

6. In a machine of the class described, the 60 combination of a structural base, a frame, three bending rolls, one disposed above the other two, journaled bearings securing said bending rolls within the frame, selective manipulative means for driving each of

said bending rolls, power driven screw means for raising and lowering the lower bending rolls, roller supports superposed above the screw means and adapted to support the lower bending rolls centrally the 70 ends of their rolling surfaces, a movable outer bearing for the upper bending roll, hydraulic means for engaging and disengaging said movable outer bearing of the upper bending roll, means whereby the rolling pressure is transmitted from the movable outer bearing to the structural frame when engaged, and means for rotating the movable outer bearing about a longitudinal horizontal axis when disengaged from said 80 upper bending roll.

7. In a machine of the class described, a fabricated base, a frame, one upper and two lower bending rolls mounted in the frame, a power unit mounted upon the base, transmission means for connecting the power unit with the bending rolls, manipulative means for rotating said bending rolls, selective means for raising and lowering either of the lower bending rolls, means for centrally supporting said rolls when raised or lowered, said means comprising a screw, a yoke supported upon the upper end of said screw, a screw wheel and a worm screw mounted on a driven shaft; a movable outboard bearing for the upper bending roll, and hydraulic means for engaging and disengaging the movable outboard bearing of the upper bending roll, said means comprising a cylinder, a piston within the cylinder, and fluid pressure means; a yoke and a piston rod connecting the yoke to the piston.

8. In a machine of the class described, the combination of a superposed roll and two lower rolls, power means adapted to drive 105 said rolls, a movable bearing adapted to support the superposed roll upon its end opposite the driven end, hydraulic means adapted to move the bearing into and out of relation with said roll, a journal whose 110 central line is parallel with the longitudinal center line of the superposed roll, revolubly supporting said bearing; and means permitting the bearing to be rotated about said journal.

9. In a machine of the class described, the combination of one upper and two lower bending rolls, all adapted to be driven at one end, a movable bearing for the end opposite the driven end of the upper bending roll, a 120 rotatable bearing support for said movable bearing, means adapted to drive and to impart rotation to said bending rolls, a frame structure supporting the bending rolls; a hydraulic cylinder, a piston and piston rod 125 adapted to the cylinder, a stirrup structure secured to said rotatable bearing support, said stirrup structure adapted to being actuated by the piston and piston rod, and a barrel like structure within the bearing sup-

port adapted to slidable relationship with and rotation about said hydraulic cylinder.

10. In a machine of the class described, a frame, a base, an upper and two lower rolls mounted in the frame, all adapted to be driven at one end, a bearing for the upper roll, means for raising and lowering each of the lower rolls, means for centrally supporting each of the lower rolls while stationary and during the period of being raised and lowered, said means comprising a driven worm, a worm wheel, a threaded screw coacting with the worm wheel and adapted to being raised and lowered thereby, a roll supporting yoke fitted to the upper end of the screw and means for supporting the worm wheel within the frame.

11. In a machine of the class described, a frame a base, an upper and two lower rolls mounted in the frame, all adapted to be driven at one end, a bearing for the upper roll, hydraulic means for engaging and disengaging the bearing from the end of the upper roll opposite its driven end, said means comprising a cylinder, a piston within the cylinder, and fluid pressure means; a yoke, a piston rod connecting the yoke to the piston, means for transmitting rolling pressure from the upper roll through its bearing and the yoke to the frame, means for raising and lowering each of the lower rolls, means for centrally supporting each of the lower rolls while stationary and during the period of being raised and lowered, said means comprising a driven worm, a worm wheel, a threaded screw coacting with the worm wheel and adapted to being raised and lowered thereby, a roll supporting yoke fitted to the upper end of the screw, and means for supporting the worm wheel within the frame.

12. In a machine of the class described, a bending roll and a movable bearing therefor,

hydraulic means adapted to move said bearing out of engagement with said bending roll, and said movable bearing when so moved out of engagement, adapted to be rotated about a horizontal axis, whose longitudinal axial line is parallel to the longitudinal axial line of said bending roll.

13. In a machine of the class described, a combination of a structural base, a frame, three bending rolls, one disposed above the other two, journaled bearings securing said bending rolls within the frame, selective manipulative means for driving each of said bending rolls, power driven screw means for raising and lowering the lower bending rolls, roller supports superposed above the screw means and adapted to support the lower bending rolls centrally the ends of their rolling surfaces, a movable outer bearing for the upper bending roll, a fluid pressure means for engaging and disengaging said movable outer bearings of the upper bending roll, means whereby the rolling pressure is transmitted from the movable outer bearing to the structural frame when engaged, and means permitting the rotation of the movable outer bearing about a longitudinal horizontal axis when disengaged from said upper bending roll.

14. In a machine of the class described, the combination of a superposed roll and two lower rolls, power means adapted to drive said rolls, a movable bearing adapted to support the superposed roll upon its end opposite the driven end, a fluid pressure means adapted to move the bearing into and out of relation with said roll, a journal whose central line is parallel with the longitudinal center line of the superposed roll; revolvably supporting said bearing; and means permitting the bearing to be rotated about said journal.

JOHN S. BEALL.
